UNITED STATES PATENT OFFICE.

CHARLES A. JOBSON, OF LOCK HAVEN, PENNSYLVANIA, ASSIGNOR TO NEW YORK AND PENNSYLVANIA COMPANY, OF LOCK HAVEN, PENNSYLVANIA, A CORPORATION OF PENNSYLVANIA.

PROCESS OF REFINING CRUDE TURPENTINE.

No Drawing.

Application filed November 22, 1920. Serial No. 425,864.

To all whom it may concern:

Be it known that I, CHARLES A. JOBSON, a citizen of the United States, residing at Lock Haven, in the county of Clinton and State of Pennsylvania, have invented certain new and useful Improvements in Processes of Refining Crude Turpentine, of which the following is a specification.

This invention is a novel process for the purification and deodorization of crude turpentine. The process is applicable broadly to the treatment of crude turpentine, from any source, but is applicable with special advantage to the refining of the crude by-product turpentine produced during the cooking or digestion of the various species of pine and coniferous woods by the so-called "soda" and "sulfate" processes. As is well known, this crude product is practically valueless, owing to its contamination by coloring matters and by ill-smelling impurities such as methyl-mercaptan, allyl-mercaptan, and analogous sulfur-containing compounds. By my process this crude material may be transformed into a practically colorless refined product of agreeable odor, essentially identical in its physical constants with gum turpentine.

Following is an example of my process in its preferred embodiment, it being understood that the invention is not limited to the particular manipulations, or to the proportions of ingredients therein set forth in detail; since these will naturally vary considerably according to nature of the crude product to be refined.

I provide an open tank which may be of wood, equipped with a mechanical agitator and with a perforated coil or equivalent device for the admission of compressed air. Into this I charge a mixture comprising approximately:

Crude turpentine----- 1 part by volume
Water----- 1.5 " " "
45 Hypochlorite solution 0.75 " " "

I prefer to use bleach liquor, such as a solution of so-called chlorid of lime or bleaching powder, having a concentration of about 4° Bé, or its equivalent in the

form of bleaching powder, sodium hypochlorite or the like. The mixture is then thoroughly agitated and aerated for a considerable period, or until the completion of the initial reaction, which usually requires not less than one hour. During this step of the process, which may be carried out at ordinary or somewhat higher temperatures, a reaction occurs which results in the formation of a flocculent precipitate containing or consisting of pinene hydrochloride. At the same time gaseous products or vapors having a strong, pungent and disagreeable odor are eliminated. During this step a portion of the coloring matter of the crude turpentine is taken up by the aqueous solution, and the disagreeable odor of the crude material is for the most part dispelled.

At the conclusion of the agitating step the entire volume of liquor, including the flocculent precipitate, is run into a still which may be of any standard type and construction, equipped with a reflux condenser or rectifying column, and with a final cooled condenser. The distillation is carried out in the usual manner, the heat being preferably applied either by means of closed steam coils, or by perforated steam coils, or by both of these means. Distillation in a current of steam is preferred since thereby the turpentine may be distilled over at relatively low temperatures, of the order of 95-97°C. During this stage of the process the pinene hydrochloride undergoes decomposition, or hydrolysis, yielding its pinene in a state of substantial purity.

The distillate consists of water and turpentine in variable proportions, easily separated from each other by the usual methods. The turpentine corresponds closely in boiling points, specific gravity and other constants to the best commercial grades, and is in every respect a desirable commercial product. An oily residue remaining in the still and not as yet fully identified, possesses qualities indicating a marketable material.

I claim:—

1. Process of refining crude turpentine

comprising reacting thereon with a hypochlorite in presence of water and thereafter subjecting the product to distillation.

2. Process according to claim 1 in which
- 5 the crude turpentine is subjected to the joint action of hypochlorite and air.
3. Process according to claim 1 in which

the crude turpentine is derived as a by-product from the digestion of coniferous woods.

In testimony whereof, I affix my signature.

CHARLES A. JOBSON.
